US00D933240S

(12) **United States Design Patent** (10) **Patent No.:** **US D933,240 S**
(45) **Date of Patent:** **** Oct. 12, 2021**

(54) **UROFLOWMETER**

- (71) Applicant: **ClearTrac Technologies, LLC**,
Elizabethton, TN (US)
- (72) Inventors: **Brent Laing**, Greenwood Village, CO
(US); **John Green**, Elizabethton, TN
(US); **Paul R. Johnson**, Boulder, CO
(US); **Robert John Smith**, Louisville,
CO (US); **Robert Edwin Schneider**,
Erie, CO (US); **Magnus Hargis**,
Hudson, CO (US); **Elise Geolat Edson**,
Boulder, CO (US); **Elizabeth A.
O'Brien**, Louisville, CO (US); **Joseph
L. Kapushion**, Westminster, CO (US)
- (73) Assignee: **CLEARTRAC TECHNOLOGIES,
LLC**, Elizabethton, TN (US)

(**) Term: **15 Years**

(21) Appl. No.: **29/707,604**

(22) Filed: **Sep. 30, 2019**

Related U.S. Application Data

- (63) Continuation of application No. 29/682,876, filed on
Mar. 8, 2019.
- (51) **LOC (13) Cl.** **24-02**

CLAIM

The ornamental design for a uroflowmeter, as shown and described.

DESCRIPTION

FIG. 1 shows a front perspective view of a uroflowmeter; FIG. 2 shows a right elevation view of the uroflowmeter of FIG. 1; FIG. 3 shows a left elevation view of the uroflowmeter of FIG. 1; FIG. 4 shows a front elevation view of the uroflowmeter of FIG. 1; FIG. 5 shows a rear elevation view of the uroflowmeter of FIG. 1; FIG. 6 shows a top view of the uroflowmeter of FIG. 1; and, FIG. 7 shows a bottom view of the uroflowmeter of FIG. 1. The broken lines in FIGS. 1-7 illustrate portions of the uroflowmeter that form no part of the claimed design.

1 Claim, 4 Drawing Sheets
